SAFETY GROUND CLAMP

George G. Truax, Renton, Pa.

Application June 26, 1945, Serial No. 601,593

4 Claims. (Cl. 173—273)

1

This invention relates to mine railways, and more particularly to a ground clamp device for an electric mine railway.

A main object of the invention is to provide a novel and improved ground clamp device adapted to be secured to a rail and to be held in clamped position thereon while the mine locomotive is moving away from the point of securing but to become automatically disengaged from the rail as the locomotive approaches said point on its return path of travel.

A further object of the invention is to provide an improved rail connector device for an electric mine locomotive which is simple in construction, easy to apply to a rail, and automatic in its disengagement from the rail when the locomotive reaches a point adjacent the connector on its return trip toward said connector.

Further objects and advantages of the invention will appear from the following description and claims, and from the accompanying drawing, wherein:

Figure 1 is a perspective view showing the rail connector device applied to the rail of a mine railway in operating position.

Figure 2 is a view in side elevation of the connector device employed in Figure 1.

Figure 3 is a bottom view of the connector device of Figure 2.

Figure 4 is a cross-sectional view taken on line 4—4 of Figure 2.

Ordinarily the main passages in a mine are equipped with trolley wires and the mine locomotives take their current from the wires by a trolley pole and wheel collector, but when the locomotive leaves the main line and runs on temporary tracks where the trolley wire has not been extended, it becomes necessary for the locomotive to take its current through a two-wire cable carried on a reel under tension mounted on the upper portion of the locomotive. In this procedure, one wire of the cable is connected with the trolley wire and the other wire is connected to the track adjacent the point where the temporary track branches off from the main line track. The cable is unwound from the reel as the locomotive moves away from the junction point and is automatically rewound as the locomotive returns toward said point. Hitherto it has been necessary for the operator to detach the rail connector by hand when the locomotive returns to the junction point. Quite frequently the locomotive operator, when returning to the junction point with a loaded train, is unable to stop and frequently runs over the cable, causing short circuits and other

2

damage to the equipment. Also, the necessity for manual removal of the connector creates a danger of shock and possible injury to the trackman from the advancing locomotive. It is therefore a prime purpose of this invention to provide a rail connector which will automatically become disengaged from the rail as the locomotive approaches on its return trip.

Referring to the drawing, 1 designates the cable which is wound on a reel carried on the upper portion of the locomotive and is maintained in tension thereby. Cable 1 comprises two wires, a first wire 2 being hooked over the trolley wire 3 and the second wire 4 being connected to a rail clamp member 5. Rail clamp member 5 comprises a rail-engaging portion 6 and a laterally extending arm portion 7 to the end of which wire 4 is connected. Rail-engaging portion 6 comprises a generally channel-shaped body adapted to fit over the rail head, the side walls of said body being inwardly converged from the front and rear ends of the body to define a central constricted region adapted to closely fit and frictionally engage the rail head when cable 1 is in tension. At diagonally opposite corners of portion 6 the side walls are formed with triangular lug elements 8, 8 adapted to underlie the rail head when the connector has been rotated into gripping position, said lug elements defining a passageway for receiving the rail head in the process of mounting the connector thereon. To facilitate the automatic disengagement of the connector from the rail, the wall surfaces 9, 9 opposite lug elements 8, 8 are downwardly and outwardly inclined with respect to said lug elements.

When cable 1 is in tension the connector is maintained in a rotated position wherein lugs 8, 8 underlie the rail head and the connector is clamped to the rail head by frictional binding of the inner side wall surfaces of the channel-shaped body therewith. When the tension on cable 2 is substantially reduced or relaxed as the locomotive returns toward the connector the connector releases its grip on the rail and may be rotated from engagement with the rail head by the upward force applied to arm 7 by cable 1 as the locomotive approaches the point of connection. In the released position there is sufficient clearance between lugs 8, 8 and the opposing outwardly inclined wall surfaces of the channel-shaped body to allow the connector to be thus rotated out of engagement with the rail head by the upward component of force exerted by the cable on the approaching locomotive.

While a specific embodiment of a connector

3

device for an electric mine locomotive has been disclosed in the foregoing description, it will be understood that various modifications within the spirit of the invention may occur to those skilled in the art. Therefore, it is intended that no limitations be placed on the invention other than as defined by the scope of the appended claims.

What is claimed is:

1. A rail clamp device comprising a generally channel-shaped body member adapted to engage a rail head and an arm extending laterally from said body member, the inner side wall surfaces of said body member converging to define a reduced intermediate section adapted to frictionally grip a rail head, diagonally opposite end portions of said inner wall surfaces being downwardly and outwardly inclined.

2. The structure of claim 1, and wherein an inwardly extending lug member is provided on the side wall opposite each of the downwardly and outwardly inclined surfaces, said lug members defining a rail head-receiving space with respect to said inclined surfaces.

3. A rail connector device for a mine locomotive comprising a generally channel-shaped body member adapted to engage a rail head and an arm extending laterally from said body member, the inner side wall surfaces of said body member converging from the front and rear ends of said member to define a reduced intermediate section adapted to frictionally grip a rail head, diagonally opposite end portions of said inner wall surfaces being downwardly and outwardly inclined, and the other diagonally opposite end portions of said inner wall surfaces being formed with inwardly projecting lug elements adapted to underlie the rail head.

4. The structure of claim 3, and wherein said lug members define a rail head-receiving space with respect to said inclined wall surfaces, the space provided being such that the connector device may be rotated off the rail head by a light upward force applied to the arm.
